(57) **CLAIM**

The ornamental design for an adjustable garage door opener mount, as shown and described.

DESCRIPTION

FIG. 1 is a front perspective view of an adjustable garage door opener mount according to the invention;

FIG. 2 is a right side elevation view of the adjustable garage door opener mount depicted in FIG. 1;

FIG. 3 is a left side elevation view of the adjustable garage door opener mount depicted in FIG. 1;

FIG. 4 is a rear elevation view of the adjustable garage door opener mount depicted in FIG. 1;

FIG. 5 is a top plan view of the adjustable garage door opener mount depicted in FIG. 1;

FIG. 6 is a front elevation view of the adjustable garage door opener mount depicted in FIG. 1; and,

FIG. 7 is a bottom plan view of the adjustable garage door opener mount depicted in FIG. 1.

Structure depicted in broken lines is for the purpose of illustrating environment and forms no part of the claimed design.
